United States Patent Office

Des. 201,130
Patented May 18, 1965

201,130

SOFA

Adrian M. Pearsall, Forty Fort, Pa., assignor to Craft
Associates, Inc., Wilkes-Barre, Pa., a corporation of Pennsylvania

Filed Apr. 14, 1964, Ser. No. 79,483

Term of patent 14 years

(Cl. D15—11)

I claim:

The ornamental design for a sofa, substantially as shown.
